CHANNEL SUPPORT FOR BRICKS

Eugene Wallace, Detroit, Mich., assignor to
David A. Wallace, Detroit, Mich.

Application February 19, 1936, Serial No. 64,643

15 Claims. (Cl. 72—19)

The present invention relates to means for supporting bricks in a building structure, and has special reference to structures such as are disclosed in the co-pending application of David A. Wallace, filed December 13, 1935, Serial No. 5 54,182, on which this invention constitutes an improvement.

The primary object of the present invention is to provide means for supporting a plurality of 10 bricks in strip form whereby they may be assembled in a wall as a single unit, the means being such that it is adapted to be secured directly to a building frame or to an existing wall to support the bricks after they are assembled in the wall. 15 The means thus provides for the individual support of each horizontal row of bricks and the mortar, which subsequently to the wall assembly is placed in the voids between the bricks, assumes none of the load of supporting the bricks. The 20 means for supporting the bricks, as in the case referred to above, constitutes a metal channel and this invention has to do more particularly with certain structural features which increase the efficiency of the channel for its intended purpose.

In the present case the channels include two parallel, or substantially parallel, side walls so formed and supported by the web portion of the channel that they exert a comparatively high degree of pressure inwardly upon bricks received within the channels. In addition, the edges of the channel side walls are bent inwardly so that instead of providing a surface contact between the channel side walls and the bricks, the contacting surface on the channels is only equal to the cross sectional thickness thereof. This comparatively narrow contacting surface on the channel, combined with a high degree of pressure results in an important feature of the invention. For example, the channels are made in lengths whereby they support several bricks and a preferred mode of assembly is to insert the bricks at one end of the channel and slide them lengthwise to their proper position with respect thereto. During this sliding movement the knife-like edges on the channels press against the flat surfaces of the bricks and wear a groove in the surfaces of the bricks, and although this groove is hardly appreciable it is a fact that it is present and it materially increases the holding action of the channel with respect to the bricks. This function may be increased by roughening the contacting surfaces on the channels, as by filing, but for ordinary purposes the 55 edges of the strip as originally cut are sufficiently

rough to provide for the wearing of a groove in the bricks.

The channels, with the bricks held therein, are assembled in parallel spaced apart relation on a building structure, and subsequently to such assembly mortar is placed in the voids between the bricks and fills the spaces between adjacent pairs of channels. After the mortar sets it rigidifies the side walls of the channels and positively holds them in engagement with the bricks. In connection with the insertion of mortar in this manner it is another object of the invention to provide the channels with means for increasing the effectiveness of the bond between the mortar and the channels so as to eliminate any possibility of the 15 mortar being removed from between the bricks and channels.

With the above and other ends in view the invention is more fully disclosed with reference to the accompanying drawing, in which

Figure 1 is a side elevation of a channel and brick assembly;

Fig. 2 is a transverse section thereof;

Fig. 3 is an elevation illustrating a detail of construction;

Fig. 4 is a transverse section thereof;

Fig. 5 is an elevation illustrating a mortar bonding means;

Fig. 6 is a transverse section thereof;

Fig. 7 is an elevation illustrating another form 30 of mortar bonding means;

Fig. 8 is a transverse section thereof;

Fig. 9 is an elevation illustrating still another form of mortar bonding means, and

Fig. 10 is a transverse section thereof.

Like characters of reference are employed throughout to designate corresponding parts.

Referring to Figs. 1 and 2 the numeral 1 designates the web part of a metal channel having flexible side walls 2 with inwardly directed portions 3 at their upper edges. Welded to the web 1 of the channel is a reinforcing strip having lengthwise extending corrugations 4 and laterally projecting flange forming portions 5, the portions 5 providing a means through which nails 45 or other securing elements may be driven to secure the channels to a wood support, such as the joists of a wood frame building. In cases of metal building frames the portions 5 will be bolted to the metal frame members, or if desired, they may be welded to the metal frame members.

Received within the channel are bricks 6 and the mode of inserting the bricks is preferably by lengthwise sliding movement. That is to say,

- the bricks are inserted one after another in the end of the channel and then slid lengthwise thereof to their proper position. Due to the comparatively narrow width of the edge surfaces of 5 the inturned portions 3 which engage the sides of the bricks, the sliding movement of the bricks relative to the channels causes a slight groove to be worn in the bricks which increases the holding action of the channels with respect to the bricks.
- 10 Obviously, in order to have such a wearing function it is necessary that the inward pressure of the side walls of the channel must be fairly high. The necessary pressure is attained by reinforcing the web 1 so that it cannot flex.
- 15 In forming a unit of a single channel with a plurality of bricks therein it is obvious that irregularities in the size of the bricks would effect the holding action of the channel with respect to the bricks. For example, if one of the bricks 20 happened to have a local high spot, this high spot would be the only part engaged by the channel side wall, or if one brick were wider than the next one the widest brick would space the channel walls so that under ordinary circum-
- 25 stances the narrow brick would not be securely held. To overcome this undesirable feature the side walls 2' of the channel are provided with a series of spaced apart kerfs 7 as illustrated in Figs. 3 and 4, so that the retaining walls adapt 30 themselves to local irregularities in the individual bricks and also to irregularities in the sizes of different bricks. In addition, each kerf presents a gouging joint which increases the groove wearing function referred to above.
- 35 In addition to the kerfs 7, Figs. 5 and 6 illustrate another feature of the invention. The side walls 2', having the kerfs 7 therein and the in-turned portions 3' for engagement with the bricks 6', instead of being integrally united by a one 40 piece web as described in connection with Fig. 2 are provided with inwardly directed portions 1' which are welded to the reinforcing strip 4'.
- In the form illustrated in Figs. 5 and 6 the web 1a of the channel has a series of lengthwise 45 extending corrugations 8 and a flat strip 4a is welded thereto to reinforce it to such an extent that it cannot flex. In this form the side walls 9 of the channel have a series of apertures 10 which provide for bonding of mortar between adjacent 50 pairs of channels when such channels are assembled in a wall. In this form the walls 9 have inwardly directed portions 11 which engage the bricks 12 and therefore a space 6 is present between the walls 9. When plastic mortar is placed 55 in contact with the outside surfaces of the walls 9 the mortar flows through the apertures 10 and becomes bonded thereto when it sets.
- In the form shown in Figs. 5 and 6, as in the forms described above, the reinforcing member 60 4a is extended beyond the side walls of the channel side walls 9 in such manner to provide means for securing the channels to supports, the extended portions of the reinforcements being designated by the characters 5a and 5b. It will be 65 noted that the projecting parts 5b are offset from the plane of the portions 5a so that when a plurality of channels are placed side by side the parts 5a of one channel may be locked beneath the parts 5b of the next adjacent channel.
- 70 As illustrated in Figs. 7 and 8, the side walls 13 may be provided with a plurality of outwardly bent arms 14 which become imbedded in mortar placed between adjacent channel walls when the channels are assembled in a wall. The arms 14 75 thus increase the bonding action between the

channels and the mortar, and in addition, the formation of each arm 14 results in a gouge-like point which increases the groove wearing action above referred to.

As illustrated in Figs. 9 and 10 the channel walls 15 may be provided with a series of prongs 16 which are bent outwardly thereof so as to be imbedded in the mortar referred to above. In the forms illustrated in Figs. 7 and 8 and in Figs. 9 and 10, the reinforcing element, described in connection with the other forms, is dispensed with. Fig. 8 illustrates a nailing flange 17 formed integral with the side walls 9 and web 7, whereas in Fig. 10 the nailing flange is dispensed with. In this latter form the channel will be secured 15 to supports by nailing at the spaces 18 between adjacent bricks 19.

Although specific embodiments of the invention have been illustrated and described it will be understood that various changes may be made 20 within the scope of the appended claims without departing from the spirit of the invention, and such changes are contemplated.

What I claim is:—

1. A channel shaped body having resiliently 25 yieldable side walls, facing elements received in said channel shaped body, said side walls having comparatively narrow contact surfaces disposed inwardly of the channel shaped body with respect to the inner surfaces of said side walls and 30 engaging adjacent surfaces of said facing elements, said contact surfaces normally being spaced apart a distance less than the width of said facing elements whereby the latter are held between said contact surfaces by friction induced 35 through inserting them therebetween.

2. In combination, a channel having resiliently yieldable side walls, facing elements received in said channel, said side walls having their edges bent inwardly of the channel whereby the comparatively narrow edge surfaces thereof engage adjacent surfaces of the facing elements to retain them within said channel, said edge surfaces normally being spaced apart a distance 40 less than the width of said facing elements whereby the latter are held between said contact surfaces by friction induced through inserting them 45 therebetween.

3. In combination, a channel having resiliently yieldable side walls, facing elements received 50 in said channel, said side walls having their edges bent inwardly of the channel whereby the comparatively narrow edge surfaces thereof engage the facing elements to retain them within said channel, the side walls of said channels having 55 a plurality of spaced apart kerfs.

4. In combination, a channel having resiliently yieldable side walls, facing elements received in said channel, said side walls having their edges bent inwardly of the channel whereby the comparatively narrow edge surfaces thereof engage the facing elements to retain them within 60 said channel, the edge surfaces of said side walls being rough whereby lengthwise sliding movement of said facing elements with respect to the channel causes said surfaces to wear a groove in the surfaces of said facing elements.

5. In combination, a channel having resiliently yieldable side walls, facing elements received in said channel, said side walls having their edges 70 bent inwardly of the channel whereby the comparatively narrow edge surfaces thereof engage the facing elements to retain them within said channel, the side walls of said channels having a plurality of spaced apart kerfs, the said kerfs 75

adapting said side walls for the retention of facing elements having surface irregularities and presenting a plurality of gouge-like points in said edge surfaces whereby lengthwise sliding movement of the facing elements with respect to the channel causes a groove to be formed in the surfaces thereof.

6. In combination, a channel having resiliently yieldable side walls, facing elements received in said channel, said side walls having their edges bent inwardly of the channel whereby the comparatively narrow edge surfaces thereof engage the facing elements to retain them within said channel, the side walls of said channel being severed at spaced points to provide outwardly directed mortar bonding means.

7. In combination, a channel having resiliently yieldable side walls, facing elements received in said channel, said side walls having their edges bent inwardly of the channel whereby the comparatively narrow edge surfaces thereof engage the facing elements to retain them within said channel, the side walls of said channel being severed at spaced points to provide outwardly directed mortar bonding means, the severed formation of said side walls being such as to present a plurality of gouge-like points in the edge surfaces of said side walls whereby lengthwise movement of the facing elements with respect to the channel causes grooves to be formed in the surfaces of said facing elements.

8. In combination, a channel having resiliently yieldable side walls, facing elements received in said channel, said side walls having their edges bent inwardly of the channel whereby the comparatively narrow edge surfaces thereof engage the facing elements to retain them within said channel and whereby the inner surfaces of the walls are spaced from the engaged surfaces of said facing elements, said side walls being formed with mortar bonding means adapted to permit mortar to enter the spaces between said side walls and facing elements.

9. In combination, a channel having resiliently yieldable side walls, facing elements received in said channel, said side walls having their edges bent inwardly of the channel whereby the comparatively narrow edge surfaces thereof engage the facing elements to retain them within said channel and whereby the inner surfaces of the walls are spaced from the engaged surfaces of said facing elements, said side walls being formed with mortar bonding means, said mortar bonding means comprising spaced apertures in said side walls through which mortar may seep into spaces between the side walls and the facing elements.

10. In combination, a channel having resiliently yieldable side walls, facing elements received in said channel, said side walls having their edges bent inwardly of the channel whereby the comparatively narrow edge surfaces thereof engage the facing elements to retain them within said channel, said side walls being formed with mortar bonding means, said mortar bonding means comprising spaced prongs projecting outwardly of the side walls.

11. In combination, a channel having resilient-

ly yieldable side walls, facing elements received in said channel, said side walls having their edges bent inwardly of the channel whereby the comparatively narrow edge surfaces thereof engage the facing elements to retain them within said channel, said channel having integrally united outwardly directed retainer receiving flanges extending throughout the length thereof whereby the same may be attached to supports between the ends of the facing elements.

12. In combination, a channel having resiliently yieldable side walls, facing elements received in said channel, said side walls having their edges bent inwardly of the channel whereby the comparatively narrow edge surfaces thereof engage the facing elements to retain them within said channel, said channel having a web portion integrally uniting said side walls and having a series of corrugations therein, and a reinforcement united with said web and preventing flexing thereof, said reinforcement comprising a plate which cooperates with said corrugations to provide a plurality of dead air spaces.

13. In combination, a channel having resiliently yieldable side walls, facing elements received in said channel, said side walls having their edges bent inwardly of the channel whereby the comparatively narrow edge surfaces thereof engage the facing elements to retain them within said channel, said channel having a web portion integrally uniting said side walls, and a reinforcement united with said web and preventing flexing thereof, said reinforcement being extended beyond the planes of the side walls and providing a flange adapted to be secured to a support.

14. In combination, a channel having resiliently yieldable side walls, facing elements received in said channel, said side walls having their edges bent inwardly of the channel whereby the comparatively narrow edge surfaces thereof engage the facing elements to retain them within said channel, said channel having a web portion integrally uniting said side walls, and a reinforcement united with said web and preventing flexing thereof, at least one of the web or reinforcement being provided with a series of corrugations providing a dead air space between the web and reinforcement.

15. In combination, a channel having resiliently yieldable side walls, facing elements received in said channel, said side walls having their edges bent inwardly of the channel whereby the comparatively narrow edge surfaces thereof engage the facing elements to retain them within said channel, the side walls of said channels having a plurality of spaced apart kerfs, said kerfs adapting said side walls for the retention of facing elements having surface irregularities and presenting a plurality of gouge-like points in said edge surfaces whereby lengthwise sliding movement of the facing elements with respect to the channel causes a groove to be formed in the surfaces thereof, and means reinforcing said channel whereby to prevent flexing thereof and to maintain the flexible side walls pressed into engagement with said facing elements.

EUGENE WALLACE.
